UNITED STATES PATENT OFFICE.

NORRIS ELMORE CLARK, OF PLAINVILLE, CONNECTICUT.

METAL-WORKING.

1,224,877.

Specification of Letters Patent.

Patented May 1, 1917.

Continuation in part of application Serial No. 869,025, filed October 28, 1914. This application filed July 10, 1915. Serial No. 39,079.

To all whom it may concern:

Be it known that I, NORRIS ELMORE CLARK, a citizen of the United States of America, and residing at Plainville, in the county of Hartford and State of Connecticut, have invented new and useful Improvements in Metal-Working, of which the following is a specification.

My invention relates to improvements in methods of and mechanism for forming what is commonly termed "expanded metal" and particularly of the type of my Patents #930,350; #1,104,476 and #1,128,659 having longitudinal strips or ribs and intervening meshwork sections.

One object is to arrange the slitting for special high speed work. The main object is to open the slitted stock rapidly and inexpensively without straining the metal or buckling the longitudinal strips. Another object is to accurately guide and fold the strips into deep ribs. Another object is to spread the meshwork sections without distorting the ribs or straining the strands. Another object is to form shoulders in the sides of the deep ribs. Another object is to open the mesh, shape the ribs and spread the fabric in a continuous operation.

The process generally is a development of that set forth in my Patents #979,130 and #1,052,888. The slitting may be accomplished for instance by tools such as shown in my Patent #1,146,554. Certain features of the improvements claimed herein were disclosed in my application #869,025 now Patent #1,146,553 and this application is accordingly a continuation of the former as to the method and mechanism now claimed therein to the extent of the disclosure therein.

As herein shown the movable or "punch" cutters are mounted to move in a direction slightly inclined relative to the horizontal. In this way as a small component of the weight always rests on the crank or eccentric shaft there is little back-lash. As the reciprocating parts move on an incline the vertical component of the weight is small and the acceleration due to gravity is slight. There is therefore a much less momentum of the moving parts on the down stroke than there would be if they moved straight up and down. This minimizes wear and permits a maximum speed of operation.

The slitted stock is fed downwardly and tangentially to spaced rolls or disks and

guides which corrugate the stock so as to gradually open the meshwork. By passing partly around these rolls and guides a relative longitudinal movement of the alternate longitudinal strips is produced so as to get a maximum expansion without buckling.

The deep ribs are formed by a series of trains of rolls after the meshwork is opened and the oppositely inclined meshwork sections assist in guiding the stock while the deep ribs are being gradually formed. After the deep ribs are formed they are spread apart by diverging rolls and guides so as to bring the meshwork into a common plane. Shallow inter-ribs may be formed at the same time.

This application also discloses details of improvement in the corrugating mechanism for opening the slitted stock and also in the deep rib forming and also in the spreading rolls as will more fully appear hereinafter.

Figure 1, is a plan view of a fragment of material slitted or scored in the preferred arrangement.

Fig. 2, is a perspective view of a fragment of one form of the finished product with alternating deep and shallow ribs.

Fig. 3, is a perspective view of another form of product with the deep and shallow ribs facing in opposite directions.

Fig. 4, is a perspective view of a fragment of product with shallow ribs only.

Fig. 5, is a sectional view of a fragment of product with deep ribs only.

Fig. 6, is a fragmentary sectional view showing a deep rib with lateral shoulders and indentations and dies for forming the same.

Fig. 7, is a diagrammatic plan view indicating the work at the different stages in the process of manufacture.

Fig. 8, is a diagrammatic side view indicating mechanism for performing the different steps of the process.

Fig. 9, is a fragmentary side view showing the fabric in the operation of opening the meshwork.

Fig. 10, is a side view of corrugating mechanism for opening the meshwork.

Fig. 11, is a side view and vertical section of part of the opening mechanism.

Fig. 12, is a fragmentary detail view of an edge holding guide.

Fig. 13, is a transverse view partly in section showing the corrugating mechanism for opening the meshwork.

Fig. 14 is a fragmentary sectional view showing a support for one of the corrugating disks or rolls.

Fig. 15, is a fragmentary sectional view showing forming and guiding members for ribs of the form shown in Fig. 5, but before completion of the ribs.

Fig. 16, is a detail side view of a rib guiding roll and its support, parts being shown in section.

Fig. 17, is a transverse sectional view of the same also showing a guide for the roll.

Fig. 18, is an enlarged fragmentary sectional view of two rib-finishing rolls.

To form a product such as shown in Fig. 2, the stock is first slitted, scored or punched as shown in Fig. 1 so as to leave unslotted strips 20, 20. The slitted section 21 is preferably made up of the two parts 22, 22 with an unslotted strip 23 between. The slits are in inclined rows so as to form strands such as 24 and 25 connected by bonds in staggered arrangement as at 26, 27 and 28. The strands in the two opposite parts 22, 22 are inclined in opposite directions from the central strip 23. The slitting does not materially stretch the strands but it may draw over the bonds slightly. The slitting mechanism is represented in Fig. 8 where 30 indicates the stationary dies or cutters. The movable cutters 31 are reciprocated on an incline beneath the stock 32 by the crank disk 33 and rod 34. The stock may be fed and guided to the slitting tools for instance by rolls 35 and guides 36.

After the stock is slitted it is passed through suitable guides to the corrugating rolls and guides in the direction of the arrow of Fig. 1 which bend the strands and open the slitted sections into meshwork such as 37 in Figs. 9 and 13. The broad unslotted strips are then passed through rolls and guides and gradually folded into ribs or beams 38. The ribs are then separated and the meshwork is spread or flattened into a common plane, if desired. The narrow unslotted strips may be ribbed as at 39 while the deep ribs are being formed, or afterward, either while the meshwork is being spread or after it is spread.

I have illustrated in Fig. 7 the formation of a fabric with three deep ribs but it is obvious that the machine may be designed to handle any number. The heavy transverse lines 40, 41, 42, 43 and 44 in Fig. 7 represent the approximate cross sectional shapes of the work at different successive stages in the process.

Each broad unslotted strip is guided around the lower face of a roll or disk 46 and supported on rolls 47 and 48 and the connecting guide 49. The rolls 46 are all mounted to rotate with shaft 50. Rolls 47 rotate with shaft 51. Rolls 48 rotate with shaft 52. Guides 49 are all carried

by cross bar 53. The upper end of each guide fits close to its roll 47 and also carries a roll 54 which runs on roll 48. Rolls 46, 47 and 48 are preferably driven. Shaft 50 is preferably carried by boxes such as 55 adjustable on an incline toward rolls 47 and 48. This shaft is preferably pressed toward rolls 47 and 48 by springs such as 56 and followers 57. The cap 58 may be removable so as to permit removal of shaft 50 and its rolls. Midway between adjacent rolls 46 is a curved member, preferably a rotatable, annular, roll or ring 60 which carries the center of the slotted section down between rolls 47 and between rolls 48. Each ring 60 has ball bearings on a carrier 61. The balls 62 may be inserted by removing the segment 63. The carriers are supported by arms 64 and 65 from cross bars 66 and 67 which are vertically adjustable in the housings so as to vary the height of the rings 60 and the extent of the action.

Tables or guides 70 are preferably provided to support the broad unslotted strips after they leave the rolls 46 and 48. Similarly a hold-down guide 71 is preferably provided carried by cross bar 67 in line with each ring 60 to guide the center of the meshwork section 37. The outer roll 46 may be provided with a flange 72 to extend over the edge of the meshwork to assist in holding the outer strip 20 in the bight of the rolls 46, 47 and 48. The outer guide 70 may also be provided with a cover 73 and flange 74 to assist in guiding the outer strip 20 after it leaves the rolls 46 and 48. The rolls 46, 47 and 48, the guides 49 and 70, the rings 60 and guides 71 are all preferably laterally adjustable to provide for stock and slitting of different widths. The upper faces of the guides 49 may be provided with a series of roller bearings to reduce the friction if desired. A band or belt may be provided around the lower rolls 47 and 48 with its upper face running beneath the roll 46 as shown in Fig. 28 of my application #863,025 to direct the unslotted strips of the stock.

After the meshwork is opened, the broad unslotted strips 20 are gradually folded, or longitudinally corrugated along the centers into the deep beams or ribs 38 by a series of die devices such as guides 75, 76 and rolls 77, 78 and 79, 80 of the proper cross sectional shape. Fig. 15 shows dies 77' and 78' for one of the intermediate forming stages of a rib 38'. This figure also shows intermediate die rolls 81 and 82 for forming a rib 23' and guides 83 and 84 for the meshwork. These guides direct the meshwork while the ribs are being formed.

After the deep ribs 38 are formed they are separated laterally by diverging trains of rolls such as 90 and 91, 92 and 93, and 94 and 95 and guides such as 96 and 97 so as

to spread or flatten the meshwork into a common plane. The intermediate strips 23 may be acted upon at the same time by rolls such as 98 and 99, 100 and 101 for feeding or shaping.

When the angle of divergence of the ribs is very great, I prefer to mount the spreading rolls so that they rotate in the plane of movement of the ribs as shown in Fig. 7 so as to prevent lateral binding. This may be readily accomplished by a universal type of connection between each roll and its shaft as shown in Figs. 16 and 17. The shaft 103 (or 103') carries a collar 104 with two pivot studs 105. On these studs is pivoted a ring 106 carrying two pivot studs 107 at right angles to studs 105. The ring 106 may be hollow and contains a lubricant for the studs 105 and 107. The roll 95 is annular in form and is pivotally carried by studs 107. In this way the roll can rotate in a plane oblique to the axis of the shaft. The plane of rotation can be determined by the guide 109 (or 109') which serves as a lateral support for the roll 95. Ball bearings 110 may be provided if desired to reduce the friction. The guide 109 may be mounted so as to permit of adjustment on its base 111 so as to vary the angle of inclination of the guide 109 if desired and thus vary the angle of divergence of the ribs. Fig. 17 also shows guides 113 and 114 for the narrow strips 23 which are here shown as flat.

After the meshwork has been spread out the ribs may be passed through one or more pairs of finishing rolls 116, 117 for instance as shown in outline in Fig. 8 and the construction of which is shown in detail in Fig. 18. Disks 120 and 121 engage the crown of the rib and may serve as feeding devices. The flanges 122 are engaged by the rolls 123 and 124 which are allowed to turn freely on the hubs 125 and 126 so as to allow for the difference in linear speed due to the different diameters of the rolls (see Fig. 18).

The product shown in Fig. 3 may be formed in a similar manner by substituting appropriate guides and rolls in place of the train of deep rib guides 75 and 76 to rolls 116 and 117 inclusive in order to form the deep ribs 130 as shown in my application #869,025.

To form the product of Fig. 4 all of the rolls and guides should be of a width, shape and spacing to handle narrow strips and open the meshwork and to form the shallow ribs 131 instead of deep ribs.

To form the product of Fig. 5 the rings 60 of the opener must be wide enough to handle the wide inter-strip for the deep rib 133 and deep rib forming rolls and guides must be substituted for the shallow intermediate rib rolls and guides. This also shows a meshwork with only six rows

of openings instead of eight and of course requires different cutters in the slitter.

The sides of the deep ribs may be treated to increase the bonding effect in the cement and concrete by providing recesses or holes 135 as shown in Fig. 3 or lateral shoulders 137 as shown in Fig. 6. The holes should be formed in the stock before forming the ribs and preferably at the same time as the slitting. The lateral shoulders may be formed by indenting the sides by rolls 138 while the rib is supported by a guide or roll 139 and its crown held down by a guide or roll 140. This is preferably done after the fabric is spread out laterally.

The action of opening the meshwork and forming the ribs being a natural continuous one the work may be fed by driving all or part of the rolls so as to give a uniform speed to all of the unslotted strips. The intermediate strips 23 as they pass around the lower faces of the rings 60 travel farther than the strips 20 and thus produce a relative longitudinal movement of the alternate strips which permits the opening to take place without any tendency to buckle or strain the metal. Whatever drag is occasioned by the rings 60 tends to hold back the inter-strips and thus facilitates the opening action.

It will be obvious that any suitable system of drive may be employed such as spur or bevel gears, chains or belts. The slitting may be performed in one machine and the remaining operations in another machine. The slitting and opening of the mesh may be performed in one machine and the rib forming and spreading in another machine, or the rib forming and spreading may be performed in separate machines.

The slitting mechanism shown being of the reciprocating step-by-step type requires that the other parts of the mechanism shall operate intermittently when coupled in a single machine. If any of the other steps are carried out in machines independent of the slitting machine they may be operated continuously. In any event a product of any desired length can be handled by this process. Lath with shallow ribs such as shown in Fig. 4 may be spread laterally by a series of trains of diverging devices such as shown in my application #747,643, now Patent #1,146,552.

By progressively moving the marginal strips as well as the centers of the slotted sections on curved lines out of their original plane it is possible to maintain the principal parts of the strands parallel to each other during the opening action and thus prevent buckling of the unslotted strips.

The oppositely inclined meshwork sections serve to guide the unslotted strips accurately during the formation of the ribs, the main ribs guide the stock during the lateral

spreading action, and the simultaneous corrugation of the interribs facilitates the action.

What I claim is:—

5 1. The method of forming expanded metal which comprises forming oppositely inclined rows of slits in a section of stock between unslotted strips, then feeding said unslotted strips forward on curved lines and simultaneously carrying the center of the slotted section around another curved line to a plane parallel with but spaced apart from the plane of the unslotted strips thereby producing a relative longitudinal movement between the unslotted strips and the center of the slotted section and opening the meshwork.

20 2. The method of forming reticulated fabric which comprises scoring certain sections along diagonal lines in staggered arrangement and leaving unscored strips at the edges and between the scored sections, then corrugating the sheet and moving all the strips in the same direction out of their original plane beginning at one end of the sheet and progressing gradually along curved lines, alternating strips at a given transverse section moving out of their original plane in advance of the other strips and 30 opening the meshes adjacent the first mentioned strips in advance of the meshes adjacent the other strips.

25 3. The method of forming meshwork which consists in scoring sections of a sheet along rows alternately inclined to the right and left to form narrow strands connected in staggered arrangement and leaving unscored marginal and intervening strips, directing the unscored strips in a curved plane and 40 directing the center of each scored section in another curved plane away from the first mentioned curved plane and thereby bending the strands gradually and uniformly to open the meshwork.

45 4. The method of forming a reticulated metal fabric which comprises, scoring parallel sections of a sheet leaving unscored marginal and intermediate strips, corrugating the sheet so as to bring the alternate strips into separated parallel planes and to open the scored sections into oppositely inclined meshwork sections, then corrugating some of the unscored strips to form beams, then spreading the beams and bringing the meshwork sections all into a common plane, and simultaneously corrugating the other unscored strips.

50 5. The method of forming a reticulated fabric which comprises slitting a longitudinal section along oppositely inclined lines and in staggered arrangement to form strands inclined toward the center and leaving longitudinal marginal and central unslotted strips, feeding the slitted stock in a direction such that the strands are inclined

toward the center in the direction of feed, carrying the marginal unslotted strips into a plane inclined to the plane of feed, carrying the central unslotted strip into another plane and thereby moving the marginal unslotted strips forward relative to the central unslotted strip and opening the meshwork into oppositely inclined sections. 70

6. The method of forming a reticulated fabric which comprises slitting a longitudinal section along oppositely inclined lines and in staggered arrangement to form strands inclined toward the center and leaving longitudinal marginal and central unslotted strips, feeding the slitted stock in a direction such that the strands are inclined toward the center in the direction of feed, carrying the marginal unslotted strips into a plane inclined to the plane of feed, carrying the central unslotted strip into another plane, thereby moving the marginal unslotted strips forward relative to the central unslotted strip and opening the meshwork into oppositely inclined sections, and folding some of said unslotted strips to form channel-like ribs. 80

7. The method of forming a reticulated fabric which comprises slitting a longitudinal section along oppositely inclined lines and in staggered arrangement to form strands inclined toward the center and leaving longitudinal marginal and central unslotted strips, feeding the slitted stock in a direction such that the strands are inclined toward the center in the direction of feed, carrying the marginal unslotted strips into a plane inclined to the plane of feed, carrying the central unslotted strip into another plane, thereby moving the marginal unslotted strips forward relative to the central unslotted strip and opening the meshwork into oppositely inclined sections, folding some of said unslotted strips to form channel-like ribs and then forming the remaining unslotted strips into channel-like ribs. 100

8. The method of forming a reticulated fabric which comprises slitting a longitudinal section along oppositely inclined lines and in staggered arrangement to form strands inclined toward the center and leaving longitudinal marginal and central unslotted strips, feeding the slitted stock in a direction such that the strands are inclined toward the center in the direction of feed, carrying the marginal unslotted strips into a plane inclined to the plane of feed, carrying the central unslotted strip into another plane, thereby moving the marginal unslotted strips forward relative to the central unslotted strip and opening the meshwork into oppositely inclined sections and then spreading the meshwork into a common plane. 115

9. The method of forming expanded

130

- metal which comprises forming oppositely inclined rows of slits in a section of stock between unslotted strips, then feeding said unslotted strips forward on curved lines and simultaneously carrying the center of the slotted section around another curved line to a plane parallel with but spaced apart from the plane of the unslotted strips thereby producing a relative longitudinal movement between the unslotted strips and the center of the slotted section, folding some of the unslotted strips to form grooved rib members and then spreading the meshwork into a common plane.
10. The method of forming a reticulated fabric which consists in feeding a sheet downward on an incline and slitting portions of it while so inclined, and leaving marginal and interior unslotted strips, and carrying the alternate unslotted strips into different planes to open the slotted portions.
11. The method of forming a ribbed expanded fabric which consists in carrying alternate unslotted strips into different planes to open the meshwork, then forming corrugations in all of the unslotted strips all opening toward the same face of the fabric, and spreading the meshwork into a common plane.
12. In an expanded metal machine, inclined slitting mechanism for slitting sections of stock in an inclined position, corrugating mechanism for opening the meshwork and horizontal guides for the meshwork.
13. In an expanded metal machine, an upper set of spaced rolls, two lower sets of spaced rolls coacting therewith, a set of guides below the upper set of rolls and a set of curved guiding members extending down between the lower rolls for carrying the centers of slotted sections downwardly.
14. In an expanded metal machine, two upper sets of rotating members, a shaft for one of said sets, the other set being in the form of rings eccentrically disposed upon said shaft, and two sets of lower rotatable members coacting with one of said upper sets, the members of the other upper set being arranged so that their lower edges rotate between the members of the lower sets.
15. In an expanded metal machine, a set of spaced rolls, guiding devices for carrying unslotted strips of a partially slotted sheet around one face of said rolls and rotating members extending between said guiding devices and between said rolls for carrying the centers of the slotted sections out of the plane of the said unslotted strips.
16. In an expanded metal machine, spaced strip-engaging rolls, rotatable annular members between said rolls for carrying the centers of slotted sections out of the plane of strips on the periphery of said rolls to open the meshwork and means for adjusting said annular members to vary the opening action.
17. In an expanded metal machine, a set of upper spaced rolls, two sets of lower spaced rolls coacting therewith, curved guides between said rolls and means for adjusting the upper rolls simultaneously toward both of the sets of the lower rolls.
18. In an expanded metal machine, upper and lower sets of spaced strip feeding rolls, curved guides beneath the upper rolls and leading to the lower rolls and rotatable guiding members between the rolls of the two sets and between the curved guides.
19. In an expanded metal machine upper and lower rib guiding rolls and lateral indenting devices operating on the sides of the ribs while the ribs are supported by the guiding rolls to thereby form longitudinally extending under-cut channels.
20. In an expanded metal machine, diverging trains of rib guiding devices including ribbed and grooved rolls, transverse shafts for said rolls, a universal connection between some of said rolls and their shafts, and guides for directing said rolls to a plane of rotation in the direction of divergence of the ribs guided by said rolls.
21. In an expanded metal machine, a plurality of rotatable rolls on the same axis for engaging the crowns of the ribs and intermediate rib finishing rolls on the same axis rotatable independently of the first mentioned rolls for engaging the flanges of the ribs and other rolls co-operating with said first and second sets of rolls to finish the crowns and the flanges of the ribs.
22. In an expanded metal machine, upper and lower rib-guiding devices and lateral indenting rolls for forming shoulders in the sides of the ribs while the ribs are supported on said guiding devices.
23. The method of forming a reticulated metal product which consists in slitting portions of a sheet in staggered arrangement, leaving unslotted marginal and intermediate strips, simultaneously forming perforations in the unslotted strips on opposite sides of the center lines thereof and afterward opening the slotted portions to form meshwork and folding the perforated strips to form grooved ribs.
24. The method of forming a reticulated metal product which consists in slitting portions of a sheet in staggered arrangement, leaving unslotted strips, opening the slotted portion to form a meshwork, folding unslotted strips to form grooved ribs and then indenting the sides of the ribs to form lateral shoulders.
25. In an expanded metal machine, a series of rib-forming dies arranged to engage parallel unslotted strips of a sheet having inclined meshwork areas between said strips, oppositely inclined guides extending between

said dies for engaging the oppositely inclined sides of the meshwork between said dies and guiding said meshwork while the ribs are being formed.

5. 26. In an expanded metal machine, a series of rolls for engaging unslotted strips of a sheet having oppositely inclined meshwork sections, and oppositely and laterally inclined guides extending between said rolls and engaging one face of the meshwork to direct it between said rolls.

15. 27. In an expanded metal machine, a series of rolls for engaging unslotted strips of a sheet having oppositely inclined meshwork sections, oppositely and laterally inclined guides extending between said rolls and engaging one face of the meshwork to direct it between said rolls, and rolls between said guides for engaging part of the stock there-
20.

28. In an expanded metal machine, a series of rolls for engaging unslotted strips of a sheet having oppositely inclined meshwork sections, and two sets of oppositely and lat-
25. erally inclined guides extending between

said rolls and engaging respectively the upper and lower faces of the meshwork to direct it between said rolls.

29. In an expanded metal machine, a series of pairs of upper and lower inclined 30 stationary guides for meshwork sections, the guides of adjacent pairs being inclined in opposite directions and some of the pairs being spaced apart and means for drawing the meshwork between the upper and lower 35 guides.

30. In an expanded metal machine, a series of pairs of upper and lower inclined stationary guides for meshwork sections, the guides of adjacent pairs being inclined in 40 opposite directions and some of the pairs being spaced apart and rolls between some of said pairs of guides for drawing the meshwork between the upper and lower guides.

Correction in Letters Patent No. 1,224,877

It is hereby certified that in Letters Patent No. 1,224,877, granted May 1, 1917 upon the application of Norris Elmore Clark, of Plainville, Connecticut, for a improvement in "Metal-Working," an error appears in the printed specificatio requiring correction as follows: Page 1, line 39, for the word "now" read *not*; an that the said Letters Patent should be read with this correction therein that the same may conform to the record of the case in the Patent Office.

Signed and sealed this 26th day of June, A. D., 1917.

[SEAL.]

R. F. WHITEHEAD,
Acting Commissioner of Patents.

Cl. 164—6.6.
